UNITED STATES PATENT OFFICE.

ERNEST C. HEAD, OF VAN WERT, OHIO, ASSIGNOR TO COLBURN MACHINE TOOL COMPANY, OF FRANKLIN, PENNSYLVANIA, A CORPORATION OF PENNSYLVANIA.

CONTROL MECHANISM.

1,353,836.

Specification of Letters Patent. Patented Sept. 28, 1920.

Application filed December 20, 1917. Serial No. 208,129.

To all whom it may concern:

Be it known that I, ERNEST C. HEAD, a citizen of the United States of America, and a resident of Van Wert, Ohio, have invented 5 a new and useful Improvement in Control Mechanism, which invention is fully set forth in the following specification.

This invention relates to control mechanism and, while capable of a wide variety 10 of uses, has especial utility when applied to the control of the feed and rapid-traverse mechanism of a machine tool.

An object of this invention is to provide 15 improved control mechanism for a plurality of operative elements whereby said elements may be actuated selectively from a common point of control.

A further object of this invention is to 20 provide three or more operative elements with control mechanism whereby said elements may be actuated selectively by the operation of a single control member operatively related to all of said elements in its neutral position.

25 A still further object of this invention is to provide a plurality of elements each of which has a non-operative position and one or more operative positions with a single control device of improved construction 30 whereby said elements may be selectively actuated to cause the same to assume any of said positions.

Yet another object of this invention is to 35 provide translating mechanism with control mechanism whereby the speed and path of movement of a translatable member may be selectively controlled by the operation of a single control member.

Still another object of this invention is to 40 provide a machine tool with a single control device for predetermining the speed and direction of movement of the tool holder both vertically and horizontally.

Other objects relate to the provision of a 45 control mechanism of the type indicated that is simple in construction, flexible in use, efficient in operation, and easy of manipulation.

Stated broadly, the invention, from one 50 point of view, comprises a plurality of operative elements, shown as clutches, and control mechanism operatively related to all of said elements in its neutral position and adapted to actuate the same, said control

mechanism being so constructed as to enable 55 the selective actuation of said elements by the operation of a single control member. From another point of view, it comprises, in combination with a translatable element, mechanism for translating said element in a 60 plurality of paths, mechanism for determining whether said translatory movement shall be fast or slow, and a single control device operatively related to said mechanisms for selectively predetermining the speed and 65 path of movement of said element. Said control device, in its preferred embodiment, comprises a lever fulcrumed for universal movement, an index plate provided with slots for guiding said lever to any one of 70 its positions for causing actuation of the controlled elements, and operative connections to said controlled elements, certain of said elements, in the embodiment shown, being actuated only by a movement of said 75 lever different from that required for the actuation of other of said elements. When the connections between said lever and the elements to be controlled are mechanical, said connections may, and preferably do, 80 comprise, as shown, a plurality of movable members positioned to be operated by said lever, means whereby movement of said lever is transmitted to but one of said members, and means, constituting an interlock 85 between said members, whereby movement of the other of said members is prevented.

The invention is capable of receiving a 90 variety of mechanical expressions, one of which is shown on the accompanying drawings, but it is to be expressly understood that the drawings are for the purpose of illustration only, and are not to be construed as a definition of the limits of the invention, reference being had to the appended claims for that purpose. 95

In said drawings,—

Figure 1 is a central vertical section through the case of the control device;

Fig. 2 is a vertical transverse section on 100 line 2—2 of Fig. 1;

Figs. 3, 4 and 5 are details of members operated by the control lever;

Fig. 6 is an assembly view, partly in sectional elevation, showing certain elements 105 of the invention in their proper relation to each other;

Fig. 7 is a plan view of the control case

looking downward into the same from the direction of the line 7—7 in Fig. 6;

Fig. 8 is a front elevation of one side or half of a vertical boring and turning mill equipped with the improved control mechanism;

Fig. 9 is a side elevation of such mill;

Fig. 10 is a face view of the case cover and index plate; and

10 Fig. 11 is a fragmentary vertical section of the saddle and cross-rail.

Referring in detail to said drawings, wherein the same characters of reference are applied to the same parts in the different views, the invention is shown as applied to the control of clutch mechanism in the gear trains for causing the feed and rapid traverse movements of the tool-holder of a vertical boring and turning mill. But it is to be expressly understood that the invention is not restricted to use with clutches nor to use in this particular type of machine tool, for it is capable of use, not only with other gear elements and in other machine tools, but wherever it is desired that a plurality of elements to be controlled shall be selectively actuated from a single point.

The mill is shown as provided with the usual cross-rail 1, upon which is mounted the usual saddle 2, a feed screw 3 engaged by a nut 4 (see Fig. 11) rigidly secured to the back of said saddle being provided to cause the travel of said saddle on said rail in horizontal directions. Carried by said saddle is a vertically movable ram 5 fed in vertical directions by the coaction of a rack 6, upon the side of said ram, and a pinion 7 mounted upon a shaft 8, suitably journaled in said saddle and rotated by a worm wheel 9, which worm wheel meshes with a worm splined on feed rod 10. As the above mechanism is of known construction, further detailed explanation is deemed unnecessary.

In the operation of a boring mill, it is desirable that the feed of the saddle 2 shall cause movement of said saddle either outwardly from the center of the table or inwardly toward the center of the table. It is also desirable that the feed of the ram 5 shall cause movement of the ram either upwardly or downwardly. Furthermore, it is desirable that in addition to such feed movements, which are comparatively slow, there be movements corresponding thereto which may be made with rapidity, and which rapid movements are usually termed the "rapid traverse" of the saddle or of the ram respectively, being generally employed when resetting these elements, or when simply moving them from one position to another with the tool out of operative engagement with the work. Therefore, it will be seen that mechanism should be provided to effect the following movements of the saddle: 1st, feed to the right; 2d, feed to the left; 3d, rapid

traverse to the right; 4th, rapid traverse to the left; and also to effect the following movements of the ram: 5th, upward feed; 6th, downward feed; 7th, upward rapid traverse; and 8th, downward rapid traverse. Furthermore, it is obviously desirable that the direction and speed of such movements of the saddle and ram should be controlled from a single point. The control device of the present invention is adapted to selectively effect any of the eight movements above enumerated, by the manipulation of a single member, preferably manually operated.

Referring to Fig. 6, 11 designates a feed box containing a train of gearing through which the drive of the feed screw 3 and the feed rod 10 is transmitted. Such train of gearing may be of any suitable construction such, for example, as disclosed and claimed in my application Serial No. 201,245 filed November 10, 1917. Driven by the gearing within said feed box 11 in the form shown is a vertical shaft 12, to which is splined a bevel gear 13 in mesh with a bevel gear 14 on a shaft 15 which is mounted in a case 16. Case 16 contains two trains of gears, one constituted by gear 17 fixed to shaft 15 and gears 18 and 19 freely rotatable respectively on shafts 20 and 21 which are also mounted in said case. The other of said trains of gears is constituted by gear 22 also fixedly mounted on shaft 15, gears 23 and 24 freely rotatable on said shafts 20 and 21 respectively, and gears 25 and 26 intermeshing with and intermediate said gear 22 and said gears 23 and 24 respectively. Gears 25 and 26 therefore drive gears 23 and 24 respectively in the opposite direction to the direction of rotation of gears 18 and 19 respectively.

Also mounted on shaft 20, in the form shown, is a double-ended clutch 27, keyed to said shaft and adapted to engage coacting clutch elements on the gears 18 and 23 by movement in opposite directions from its neutral or non-operative position. The shipper sleeve of said clutch is engaged and actuated by a yoke 28 carried by the vertical rotative rod 29. By the operation of said clutch to engage the coacting clutch elements on either gear 18 or gear 23, shaft 20 will be rotated in the one direction or the other.

Mounted on shaft 21, in the construction illustrated, is a double-ended clutch 30 keyed to said shaft and adapted to engage coacting clutch elements on the gears 19 and 24 by movement in opposite directions from its neutral or non-operative position. The shipper sleeve of clutch 30 is engaged and actuated by a bell crank yoke 31 adapted to be operated by the vertically movable rod 32. By the operation of clutch 30 to engage the coacting clutch elements on either gear 19

19 or gear 24, shaft 21 will be rotated in the one direction or the other.

Trains of gearing 33 and 34, shown in dotted lines in Fig. 9, transmit the movement of shafts 20 and 21, respectively, to feed rod 10 and feed screw 3, respectively. Such trains of gearing may be of any suitable construction such, for example, as disclosed and claimed in my application Serial No. 201,246 filed November 10, 1917.

A third double-ended clutch 35 is mounted within the feed box 11, in the construction illustrated, and by movement in opposite directions from its neutral or non-operative position is adapted to clutch coacting gear elements in the drive mechanism, said gear elements preferably rotating in opposite directions and at different speeds, to respectively cause the slow or rapid rotation of shaft 12 to in turn cause the feed or rapid traverse movements of the feed screw 3 and the feed rod 10. The shipper sleeve of said clutch 35 is engaged and actuated by a yoke 36, mounted upon a vertical rotative rod 37.

The single control device of the present invention is employed, in the form shown, for selectively shifting the shipper sleeves of said respective clutches 27, 30 and 35 in either direction, said control device in its preferred embodiment being constructed as follows: Secured to the lower edge of the cross-rail 1 is a case 38 within which is inclosed or carried the main operative elements of the control device. The primary element of said device comprises a lever 39 suitably mounted for universal movement. In the form shown, said lever is provided at its fulcrum with a globular enlargement 40, and mounted within the case 38 are a seat-plate 41 and a friction or compression plate 42, suitably recessed to conform to the spherical surface of said enlargement 40. Seat plate 41 is mounted fixedly in position, while plate 42 is yieldably retained in contact with enlargement 40 by means of springs 43 carried by pins 44, which pins are suitably attached to a follower plate 45 at one end and provided at their opposite ends with heads between which and a wall of the case 38 the respective springs are retained. Plate 42 is thus yieldably retained in contact with the spherical enlargement 40, exerting a pressure thereon which causes the portions of the universal joint thus provided to be always in firm contact, and preventing said joint from becoming loose or operating too freely.

Rotatively mounted in the rear of said case 38 is an element consisting of a short shaft 46 reduced at its outer end and extending through the rear wall of said case, the opposite end of said shaft carrying a head 47 in which is provided a pair of cross-slots or grooves 48, shown as intersect-

ing at right-angles. Mounted upon the outer and reduced end of shaft 46 is a crank 49, to which is pivoted one end of a reach-rod 50, the other end of which rod is attached to a crank 51 carried by a sleeve 52 which is splined to rod 37. Sleeve 52 may be maintained in operative position in any suitable way, as by a bracket 53 suitably carried by the cross-rail 1.

The inner end of lever 39 is provided with a spherical enlargement 54, which is designed to coöperate with the slots or grooves 48 in the aforesaid head 47. To maintain said lever in its neutral position with enlargement 54 at the intersection of the slots 48, said enlargement may be provided with a depression 55, and a spring-pressed pin 56 for engagement in said depression may be mounted axially in shaft 46 with its inner end projecting into the slots 48 at the intersection of the same. Also, to maintain crank 49 at either limit of its movement, the same may, if desired, be provided with a spring-pressed ball 57 adapted to engage a pair of suitably positioned depressions 58 in the rear face of case 38.

Also carried within the case 38 is a plate 59 mounted for rectilinear movement on a pair of horizontal rods 60 and 61, and a vertically movable plate 62 mounted upon vertical rods 63 and 64 for rectilinear movement, said plate 62 being shown as operatively attached to one of said latter rods, as rod 64, to cause the vertical movement of this rod as said plate is moved vertically on the other rod. Plates 59 and 62 are mounted one in the rear of the other, and are designed to be selectively operated by movement of lever 39. To this end, plate 59 is provided with a vertically elongated opening 65 from the vertical edges of which a pair of inwardly extending lugs 66 project to a position to closely embrace the sides of lever 39, and plate 62 is provided with a horizontally elongated opening 67, from the horizontal edges of which a pair of inwardly extending lugs 68 project to a position to closely embrace the upper and lower faces of lever 39. By reason of the lugs 66 and 68 and the direction of extension of openings 65 and 67, plates 59 and 62 are respectively moved by the lever 39 only in horizontal and vertical directions.

Plate 59, in the form shown, is operatively connected to rod 29 by means of link 69 and crank 70 and rod 64 is operatively connected to rod 32 by lever 71. Therefore, with this arrangement, horizontal movements of plate 59 are transmitted to clutch 27, and vertical movements of plate 62 are transmitted to clutch 30.

Plate 59 is also preferably provided with a pair of slots or grooves 72 intersecting at right angles, as shown in Fig. 3, and plate 62 is provided with a pin 73 designed to

travel in said slots 72, and to be at the intersection of said slots when plates 59 and 62 are in their neutral or central position, as shown in Fig. 2, with lever 39 in operative relation to both pairs of lugs 66 and 68.

The face of case 38 is shown as so constructed as to provide a guide and index plate 74, through which the lever 39 extends. In the form shown in Fig. 10, said index plate is provided with a pair of vertical radially-extending slots 75, and a pair of horizontal radially-extending slots 76, each of said slots 75 and 76 being provided at its outer extremity with a transverse slot 77 extending upon either side thereof. The face of index plate 74 may be provided with suitable characters to indicate the functions which will be obtained by movement of lever 39 to the various positions to which it may be moved within the slots 75, 76 and 77.

Operation: Assume that lever 39 is in its central or neutral position, with the outer end thereof at the intersection of the slots 75 and 76 in plate 74, and with its inner end at the intersection of the slots 48 in head 47. Lever 39 will be maintained in this position by the engagement of pin 56 in depression 55 in the spherical enlargement 54 on the inner end of said lever. In this position of lever 39, all of the clutches 27, 30 and 35 are in neutral or non-operative position, with their end faces out of operative engagement with the coacting clutch elements on gears 18 and 23, 19 and 24, and the slow and fast driving elements within feed box 11. If, now, lever 39 be moved to position A or position B in slot 76, a lug 66 on plate 59 will be engaged by said lever and said plate will be shifted on its rods 60 and 61. Movement of plate 59 is transmitted through link 69, crank 70, vertical rod 29 and yoke 28 to clutch 27, to shift the same into operative engagement with the face of the coacting clutch element on gear 18 or gear 23, as the case may be. Simultaneously with the movement of plate 59 by lever 39, the inner end of said lever will move in the horizontal groove 48 in head 47, but without actuation of said head. Furthermore, upon movement of plate 59 horizontally, pin 73 will move from the intersection of slots 73 into the horizontal of said slots, interlocking the plates 59 and 62, and thereby preventing vertical movement of the latter. The horizontal elongation of opening 67 permits the said horizontal movement of lever 39 without interference, while, as soon as lever 39 moves from its central position, it is out of operative relation to lugs 68 on plate 62, and can thereafter be moved vertically in either direction, within the limits provided by the vertical extent of opening 67, without operating said plate 62. Such vertical movements of lever 39 are permitted at the outer limit of the horizontal movement of

said lever by the corresponding transverse slot 77. Movement of lever 39 in the latter slot in either direction causes a rotation of head 47, owing to the engagement of enlargement 54 with the walls of the horizontal slot 48. Rotation of head 47 is transmitted through shaft 46 to crank 49, and thence through reach-rod 50 and crank 51 to sleeve 52, whereby rod 37 is rotated to shift clutch 35 into engagement with the coacting clutch element of either the slow or the fast driving gear of the feed mechanism as lever 39 is moved in the one direction or the other in slot 77 from slot 76.

Similarly, by movement of lever 39 in the opposite direction in slot 76, plate 59 will be slid in the opposite direction to cause a shift of clutch 27 in the opposite direction and therefore a reversal in the direction of rotation of feed rod 10, clutch 35 being thereafter actuated by movement of said lever in the corresponding transverse slot 77.

If lever 39 be moved vertically to position C or to position D, plate 62 will be moved vertically in the corresponding direction, pin 73 engaging in the vertical slot 72 and preventing horizontal movement of plate 59. Simultaneously lever 39 will move out of operative relation to lugs 66, and at the extremity of its vertical movement may be moved horizontally in either direction, owing to the shape of opening 65. Vertical movement of the plate 62 is transmitted through rod 64 to lever 71, rod 32 and yoke 31, to shift clutch 30 in the one direction or the other into operative engagement with the coacting clutch element on gear 19 or gear 24, as the case may be. As above explained with relation to the movement of lever 39 vertically in transverse slots 77 at positions A or B, a similar movement of said lever horizontally in the corresponding transverse slots 77 at positions C or D will cause a rotation of the head 47 owing to the engagement in slot 48 of enlargement 54, which enlargement is now in one of the vertical slots in said head, together with a resultant actuation of clutch 35 in the one direction or the other as lever 39 is moved in the one direction or the other transversely to the vertical slot 75.

It will therefore be seen that by movement of lever 39 from its central or neutral position into one or another of the slots 75 and 76 in the index plate 74, not only the clutches 27 and 30 may be selectively actuated, but also the end of the selected clutch which is brought into coacting relationship with the clutch element on the adjacent gear is selectively determined. Therefore, by manipulation of the one lever 39, the tool holder may be fed up or down or in or out, at the option of the operator.

Furthermore, by movement of said lever in the transverse slot 77 at any one of the

positions A, B, C or D, clutch 35, while actuated non-selectively, is operated in accordance with the direction of movement of the lever in such transverse slot to selectively predetermine which end of clutch 35 shall be brought into coacting relationship with the clutch elements on the adjacent gearing to selectively determine whether the translation of the tool holder in either direction in either of its paths shall be fast or slow, *i. e.*, shall be the normal feed movement or the rapid traverse movement.

Furthermore, it will be noted that, in the arrangement shown, horizontal movements of the saddle are obtained by movement of the lever 39 in the horizontal slots 77 and that vertical movements of the ram are obtained by movement of the lever 39 in the vertical slots 77, since movement to a horizontal slot 77 is necessary to actuate clutch 30 in the driving train of the feed screw 3 and movement to a vertical slot 77 is necessary to actuate clutch 27 in the driving train of the feed rod 10. Thereafter clutch 35 is actuated by movement of lever 39 in the selected transverse-slot 77 to complete the driving train from the driving mechanism to the feed screw or feed rod, as the case may be. By casting or otherwise securing on index plate 74, adjacent the proper end of each slot 77, the characters "F" or "T", to designate "Feed" or "Rapid Traverse" respectively, the direction in which said lever is to be moved to secure the one or the other function is clearly indicated. Therefore, by associating the horizontal and vertical movements of the lever 39 with the horizontal and vertical movements of the tool holder, the selection of the proper movement of said lever is greatly facilitated, and bearing this relation in mind, the operator need only note the characters "F" and "T" to quickly secure the desired direction and nature of movement of the tool-holder. By interchanging the connections between the plates 59 and 62 and the clutches 27 and 30, however, the movement of the tool-holder could be made to conform in direction to the direction of movement of the control member 39 in the radial slots 75 and 76.

While the illustrated embodiment of this invention has been described with considerable particularity, it is to be expressly understood that the invention is not to be restricted to such embodiment, for it is capable of receiving a variety of mechanical expressions, some of which will readily suggest themselves to those skilled in the art. Thus, while the elements controlled have been shown as clutches, it is to be understood that such elements may take other equivalent forms, such for example as shiftable gears, without departing from the spirit of this invention. Again, while the

control member has been shown as mechanically connected with the elements to be controlled, it is to be understood that it is within the purview of this invention and the contemplation of the claims to embrace 70 control mechanism wherein the control member in its movements operates electrical contacts or valves to effect the selective actuation of the controlled elements through electrical devices or pneumatic or hydraulic 75 devices. Furthermore, certain features of the invention are capable of use without other features thereof. Reference is therefore to be had to the claims hereto appended for a definition of the limits of the invention. 80

What is claimed is:—

1. In combination, three or more clutches and a single control device for actuating said clutches, said control device having a 85 neutral position in which it is operatively related to all of said clutches.
2. In combination, three or more clutches and a single control device for actuating certain of said clutches selectively, said control device having a neutral position in which it is operatively related to all of said 90 clutches.
3. In combination, a plurality of clutches and a single control device operatively related thereto for actuating certain of said clutches selectively and other of said clutches non-selectively. 95
4. In combination, a plurality of clutches and a single control device operatively related thereto for actuating certain of said clutches selectively and other of said clutches non-selectively but in unison with the former. 100
5. In combination, three or more clutches, 105 actuating connections therefor, and a single control member operatively related to all of said actuating connections in its neutral position.
6. In combination, three or more clutches, 110 actuating connections therefor, and a single member for selectively controlling said connections and operatively related to all of said connections in its neutral position.
7. In combination, a plurality of clutches, 115 actuating connections therefor, and a single control member for selectively operating any one of a plurality of said connections and thereafter operating other of said connections in unison with the former. 120
8. In combination, a plurality of clutches, actuating connections therefor, and a single control member for selectively operating certain of said connections and non-selectively operating other of said connections 125 but in unison with the former.
9. In combination, three or more clutch members, each adapted to operatively engage either of a plurality of coacting clutch elements, and a single control member for 130

- actuating said clutch members selectively to operatively engage the same with either of their respective coacting clutch elements, said control member in its neutral position being operatively related to all of said clutch members.
10. In combination, three or more movable clutch members, each adapted to engage coacting clutch elements by movement 5 in opposite directions from a neutral position, and a single control member and having a neutral position in which it is operatively related to all of said clutch members for moving said clutch members selectively in either direction.
11. In combination, a translatable element, mechanism for translating said element in a plurality of paths, mechanism for rendering said translation fast or slow, and 20 a single control device operatively related to said mechanisms for selectively controlling the path and speed of said translation.
12. In combination, a translatable element, mechanism for translating said element in either direction in a plurality of paths, mechanism for rendering said translation fast or slow, and a single control device operatively related to said mechanisms for selectively controlling the path, direction and speed of said translation.
13. In combination, a translatable element, mechanism for translating said element in a plurality of paths, mechanism for rendering said translation fast or slow, 35 elements for selectively controlling the path and speed of said translation, and a single control device for said elements.
14. In combination, a translatable element, mechanism for translating said element in either direction in a plurality of paths, mechanism for rendering said translation fast or slow, elements for selectively controlling the path, direction and speed of said translation, and a single control device 40 for said elements.
15. In a machine tool, a tool-holder, mechanism for feeding said tool-holder in a horizontal direction, mechanism for feeding said tool-holder in a vertical direction, mechanism 50 for causing the rapid traverse of said tool-holder in either of said directions, and a single control device for selectively causing either the feed or the rapid traverse of said tool-holder in either of said directions.
16. In a machine tool, a tool-holder, mechanism for feeding said tool-holder in either direction horizontally, mechanism for feeding said tool-holder in either direction vertically, mechanism for causing the rapid 55 traverse of said tool-holder in either direction in either of said paths, and a single control device for selectively causing either the feed or the rapid traverse of said tool-holder in either direction in either of said 60 paths.
17. In a machine tool, a tool-holder, mechanism for feeding said tool-holder in a horizontal direction, mechanism for feeding said tool-holder in a vertical direction, mechanism for causing the rapid traverse of 70 said tool-holder in either of said directions, elements for causing either the feed or the rapid traverse of said tool-holder in either of said directions, and a single control device for selectively actuating said elements.
18. In a machine tool, a tool-holder, mechanism for feeding said tool-holder in either direction horizontally, mechanism for feeding said tool-holder in either direction vertically, mechanism for causing the rapid 80 traverse of said tool-holder in either direction in either of said paths, elements for causing either the feed or the rapid traverse of said tool holder in either direction in either of said paths, and a single control device for selectively actuating said elements.
19. In combination, a plurality of elements to be controlled, a control device for said elements comprising a lever fulcrumed for universal movement, a guide member for 90 said lever enabling movement thereof in a plurality of paths and in either direction from either of said paths, actuating connections for certain of said elements operated selectively by movement of said lever in either of said paths, and actuating connections for other of said elements operated selectively by movement of said lever in either direction from the selected path.
20. In combination, a plurality of 100 clutches, a control device for said clutches comprising a lever fulcrumed for universal movement, a guide member for said lever enabling movement thereof in either of a plurality of paths and in a direction transverse to each of said paths, actuating connections for said clutches operated selectively by movement of said lever in either of said paths, a clutch in the driving connections of said first named clutches, and 110 actuating connections for said last named clutch operated by movement of said lever transversely to the selected path.
21. In combination, a plurality of 115 clutches, a control device for said clutches comprising a lever fulcrumed for universal movement, a guide member for said lever enabling movement thereof in either of a plurality of paths and in either direction transversely to each of said paths, actuating 120 connections for said clutches operated selectively by movement of said lever in either of said paths, a speed determining clutch member in the driving connections of said first named clutches, and actuating connections for said last-named clutch member selectively operated by movement of said lever in either direction transversely to the 125 selected path.
22. In combination, a plurality of ele- 130

ments to be controlled, a control device for said elements comprising a lever fulcrumed for universal movement, a guide member for said lever enabling movement thereof in a plurality of paths and also transversely to each of said paths, actuating connections for certain of said elements operated selectively by movement of said lever in either of said paths, and actuating connections for other 10 of said elements operated only by movement of said lever transversely to the selected path.

23. In combination, a plurality of elements to be controlled, a control device for 15 said elements comprising a lever, a plurality of members adapted to be moved at an angle to each other by said lever, an interlock between said members whereby movement of one of said members prevents movement of 20 the other of said members, and actuating connections between said members and said elements to be controlled.

24. In combination, a plurality of elements to be controlled, a control device for 25 said elements comprising a lever, a plurality of members adapted to be moved at an angle to each other by said lever, means whereby movement of said lever is transmitted to but one of said members, and actuating connections between said members and said elements to be controlled.

25. In combination, a plurality of elements to be controlled, a control device for 30 said elements comprising a lever, a plurality of members adapted to be moved at an angle to each other by said lever, means whereby movement of said lever is transmitted to but one of said members, an interlock between said members whereby movement of the other of said members is prevented, and actuating connections between said members and said elements to be controlled.

26. In a machine tool, a tool-holder, 45 mechanism for feeding said tool-holder in a horizontal direction, mechanism for feeding said tool-holder in a vertical direction, mechanism for causing the rapid traverse of said tool-holder in either 50 of said directions, a control device comprising a single control member for selectively causing either the feed or the rapid traverse of said tool-holder in either of said directions, and an index plate provided with 55 horizontal and vertical guide slots for said member, said control device being so constructed that horizontal and vertical movements of said control member effect horizontal and vertical movements respectively 60 of said tool-holder.

27. In a machine tool, a tool-holder, mechanism for feeding said tool-holder in a horizontal direction, mechanism for feeding said tool-holder in a vertical direction, 65 mechanism for causing the rapid traverse

of said tool holder in either of said directions, a control device comprising a single control member for selectively causing either the feed or the rapid traverse of said tool-holder in either of said directions, and an index plate provided with horizontal and vertical guide slots for said member, said control device being so constructed that horizontal and vertical movements of said control member effect horizontal and vertical movements respectively of said tool-holder, said index plate being further provided with characters to indicate what movements of said member will effect the feed or rapid traverse of said tool-holder. 70 75 80

28. In combination, a translatable element, mechanism for translating said element in a plurality of directions, mechanism for rendering said translation fast or slow, 85 a control device comprising a single control member operatively related to said mechanisms for selectively controlling the direction and speed of said translation, and an index plate provided with guide slots certain of which conform in direction with the directions of movement of said translatable element, said control device being so constructed that movements of said control member in said last-mentioned slots effect 90 95 movements of said translatable element in the corresponding directions.

29. In combination, a translatable element, mechanism for translating said element in a plurality of directions, mechanism 100 for rendering said translation fast or slow, a control device comprising a single control member operatively related to said mechanisms for selectively controlling the direction and speed of said translation, and an 105 index plate provided with guide slots certain of which conform in direction with the directions of movement of said translatable element, said control device being so constructed that movements of said control member in said last-mentioned slots effect 110 movements of said translatable element in the corresponding directions, said index plate being further provided with characters to indicate what movements of said 115 member effect the fast or slow translation of said element.

30. In a machine tool, a plurality of elements for controlling the feed and rapid traverse of the saddle and ram, a control 120 device comprising a single control member for selectively actuating said elements, and an index plate provided with radial guide slots and vertical and horizontal guide slots transverse thereto for said control member, 125 said control device being so constructed that movements of said saddle or ram are effected by movement of said control member in said horizontal or vertical transverse guide slots respectively. 130

31. In a machine tool, a plurality of elements for controlling the feed and rapid traverse of the saddle and ram, a control device comprising a single control member for selectively actuating said elements, and an index plate provided with radial guide slots and vertical and horizontal guide slots transverse thereto for said control member, said control device being so constructed that movements of said saddle or ram are effected by movement of said control member in said horizontal or vertical transverse guide slots respectively, said index plate being further provided with characters to indicate what movements of said member will effect the feed or rapid traverse of said saddle or ram.
32. Control mechanism comprising three or more groups of co-operating elements, each of said groups having a non-operative and one or more operative positions, in combination with a single control device having a neutral position in which it is operatively related to all of said groups and movable to selectively actuate said elements to cause the same to assume any of said positions.
33. Control mechanism comprising three or more elements to be controlled, each having a non-operative position and a plurality of operative positions, in combination with a single control device for selectively actuating said elements to cause the same to assume any of said positions, said control device having a neutral position, movement from which in angularly-related directions selectively actuates certain of said elements.
34. Control mechanism comprising three or more elements to be controlled, each having a non-operative position and one or more operative positions, actuating connections for said elements, and a single control member for selectively operating said connections, said control member having a neutral position, movement from which in angularly-related directions selectively actuates a plurality of said connections.
35. Control mechanism comprising a plurality of elements to be controlled in combination with a single control device for moving into operative position certain of said elements selectively and other of said elements non-selectively and operatively related to said first-named elements in its neutral position.
36. Control mechanism comprising a plurality of elements to be controlled, actuating connections therefor, and a single control member for selectively operating certain of said connections and thereafter operating other of said connections non-selectively but in unison with the former, said control member in its neutral position being operatively related to said first-named connections.
37. Control mechanism comprising three or more elements to be controlled in combination with a single control device for selectively actuating said elements, the selective actuation of certain of said elements by said control device positioning said device in actuating relation to other of said elements.
38. Control mechanism comprising three or more elements to be controlled, actuating connections therefor, and a single control member for selectively operating said connections, the selection operation of certain of said connections by said member completing the actuating connection to other of said elements.
39. Control mechanism comprising a plurality of elements to be controlled, a single control member movable in a plurality of angularly-related paths and at an angle to each of said paths, operating connections for certain of said elements selectively actuated by movement of said member in either of said paths, and operating connections for other of said elements actuated by movement of said member at an angle to the selected path.
40. Control mechanism comprising a plurality of elements to be controlled, a single control member movable from a neutral position into any one of four angularly-related paths and movable angularly at the end of each path, operating connections for certain of said elements selectively actuated by movement of said member in either of said paths, and operating connections for other of said elements actuated only by movement of said member at an angle to the selected path.
41. Control mechanism comprising a plurality of elements to be controlled, a single control member movable in a plurality of angularly-related paths and transversely to each path in either direction, operating connections for certain of said elements selectively actuated by movement of said member in either of said paths, and operating connections for other of said elements selectively actuated by the direction of movement of said member transversely to the selected path.
42. In combination, a translatable element, mechanism for translating said element in a plurality of angularly-related directions, a single control member movable in corresponding angularly-related directions, and operating connections between said control member and said mechanism correlating the movements of said control member and mechanism so as to effect translation of said element in directions corresponding with the movements of said member.
43. In combination with a plurality of elements to be controlled, a single control member, apertured members through which said control member extends and movable

thereby, an interlock between said apertured members whereby movement of one prevents movement of the other, and operating connections between said apertured members and said elements to be controlled.

44. In combination with a plurality of elements to be controlled, a single control member, apertured members through which said control member extends and movable thereby, said apertured members being constructed to permit free transverse movement of said control member after one of said apertured members has been moved, operating connections between said apertured members and certain of said elements to be controlled, and operating connections for other of said elements actuated by said free movement of said control member.

45. In combination with a plurality of elements to be controlled, a single control member, apertured members through which said control member extends and movable thereby, a member provided with grooves in which said control member moves freely while moving said apertured members, said apertured members being constructed to thereafter permit free movement of said control member to move said grooved member, operating connections between said apertured members and certain of said elements to be controlled, and operating connections between said grooved member and other of said elements to be controlled.

46. In combination with a plurality of elements to be controlled, a single control member mounted for pivotal movement, op-

erating connections for certain of said elements to be controlled selectively actuated by pivotal movement of said member from neutral position, and operating connections for other of said elements to be controlled completed by said first named movement of said member and actuated by further pivotal movement of said member.

47. In combination with a plurality of elements to be controlled, a single control member mounted for universal pivotal movement, slidable members selectively operated by pivotal movement of said control member from neutral position, a rotatable member operated by further pivotal movement of said control member, operating connections between said slidable members and certain of said elements to be controlled, and operating connections between said rotatable member and other of said elements to be controlled.

48. In combination with a plurality of elements to be controlled, a single control member mounted for universal pivotal movement, a plurality of members operatively connected to certain of said elements to be controlled and selectively movable in either direction by movement of said control member from neutral position, and a member operatively connected to other of said elements to be controlled and selectively movable in either direction by further pivotal movement of said control member.

In testimony whereof I have signed this specification.

ERNEST C. HEAD.
